UNITED STATES PATENT OFFICE.

HEINRICH JULIUS MÜLLER, OF SCHAFFHAUSEN, SWITZERLAND.

MEANS FOR CHECKING THE SALE OF RAILWAY AND OTHER TICKETS.

No. 850,950.

Specification of Letters Patent.

Patented April 23, 1907.

Application filed October 30, 1906. Serial No. 341,228.

To all whom it may concern:

Be it known that I, HEINRICH JULIUS MÜLLER, a citizen of Switzerland, residing in Schaffhausen, in the Canton of Schaffhausen, Republic of Switzerland, (whose post-office address is 29 Neustadt, Schaffhausen,) have invented certain new and useful Improvements in Means for Checking the Sale of Railway and other Tickets; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

I have applied for patent in Switzerland on November 9, 1905, Patent No. 35,273; in Germany on November 13, 1905, Patent No. 177,632; in Austria on December 7, 1905, application A.6,477-05; in France on May 25, 1906, Patent No. 366,562; in Italy on June 2, 1906.

The object of the present invention is an arrangement for checking the railway and other tickets taken out of the pigeonholes of ticket-sale cases in which the tickets are placed on end and pushed forward by springs.

In the accompanying drawings two forms of the invention are shown.

Figure 1 is a section of the arrangement on line A B, Fig. 2, as attached to one of the pigeonholes; Fig. 2, a front view showing two forms of same in different positions; Fig. 3, a partial section on line C D, Fig. 2; Fig. 4, a plan of slide.

a is a compartment of a ticket-sale case, in which compartment the tickets are arranged vertically. d is a plate for pushing the tickets forward, being actuated by a spring f, provided with a guide-rod e. In a slot g in the bottom l of the compartment an angle-shaped slide h, which can be moved vertically, is fitted. The vertical side h' of same is provided at the top with two sidewise-projecting portions i to secure the tickets and with a handle k, while the horizontal part h² is formed with a recess h³, which embraces a piece m, which is turned down from the bottom of the compartment l. If the slide is raised by means of the handle k into the position shown in Fig. 1, it remains in that position after the handle has been released, (see Figs. 1 and 3, left-hand side,) as the vertically-arranged tickets, being actuated by the

pressure of the springs f, press forward the vertical part h' of the slide h, and the friction thereby arising between the front edge of the slot g and the part h', as well as between the front ticket and the part h' of the slide, prevents the latter from falling down automatically. The horizontal part h² of the slide when the latter is in the raised position lies against the bottom of the compartment and prevents the slide from tipping over. In this position the slide indicates to the checking official that no tickets are being taken out of the compartment in question. If the ticket clerk wants to take a ticket out of the corresponding compartment, he has only to push the tickets in the ticket-compartment slightly back—that is to say, to release the part h' of the slide from the pressure of the spring f—whereupon the slide by virtue of its own weight falls down into the bottom position and admits of the tickets being taken out in the usual way, Fig. 2, center part, and Fig. 3. When the slide falls down, the flap m causes it to descend vertically. While the slide is at the bottom the flaps i prevent the tickets from being pushed out of the cases. In this position the slide shows the ticket clerk that tickets have been withdrawn from the corresponding compartment.

In the form of the slide shown in Figs. 1 and 3 and the two left-hand sections of Fig. 2 the vertical portion h' is full, so that when raised it covers the bottom part of the foremost ticket. In the slide shown in the right-hand portion of Fig. 2 there is an opening n, which when the slide is raised shows the number of the ticket behind it.

The arrangement described has this advantage over previous devices, for the same purpose that the slide and the pushers for the tickets are all combined in one piece and there are no hinges and rivets. As in this arrangement two hitherto separate parts—that is, pushers and slide—are combined in one, the cost of making and fitting is extremely low.

What I claim is—

1. Apparatus for checking the withdrawal of tickets from the pigeonholes in railway and other ticket cases for tickets placed vertically and pushed forward by springs, comprising a slide having sidewise-projecting portions, fitted in the front part of the bottom of the pigeonhole and movable vertically, the said sidewise projections of the slide limiting its downward motion and when it is at the

bottom providing a stop for the tickets in the pigeonhole, the slide being capable of being maintained in the elevated position by means of the pressure of the spring which pushes the 5 tickets forward, substantially as described.

2. Apparatus for checking the withdrawal of tickets from the pigeonholes in railway and other ticket cases for tickets placed vertically and pushed forward by springs, comprising a slide having sidewise-projecting portions,

10 fitted in the front part of the bottom of the pigeonhole, movable vertically and having a vertical and a horizontal shank, a guide for the horizontal shank of the slide, the said 15 sidewise projections of the slide limiting its downward motion and when it is at the bottom providing a stop for the tickets in the pigeonhole, the slide being capable of being maintained in the elevated position by

20 means of the pressure of the spring which pushes the tickets forward, substantially as described.

3. Apparatus for checking the withdrawal of tickets from the pigeonholes in railway

and other ticket-cases for tickets placed vertically and pushed forward by springs comprising a slide having sidewise-projecting portions, fitted in the front part of the bottom of the pigeonhole, movable vertically and having a vertical and a horizontal shank, and a 25 flap turned down from the bottom of the pigeonhole and serving as guide for the horizontal shank of the slide, the sidewise projections of the slide limiting its downward motion and when it is at the bottom providing 30 a stop for the tickets in the pigeonhole, the slide being capable of being maintained in the elevated position by means of the pressure of the spring which pushes the tickets forward, substantially as described. 35

40 In testimony whereof I have signed my name to this specification in the presence of two subscribing witnesses.

HEINRICH JULIUS MÜLLER.
